FISHING FLOAT

Charles C. Settle, Columbus, Ind.

Application March 26, 1956, Serial No. 40,774

Term of patent 14 years

(Cl. D31—4)

Fig. 1

Fig. 2

Fig. 3

Fig. 4

Fig. 5

Figure 1 is a perspective view of a fishing float, showing my new design;

Figure 2 is an elevational view thereof;

Figure 3 is another elevational view thereof showing one of the fins in edge elevation;

Figure 4 is a bottom plan view thereof; and

Figure 5 is a top plan view thereof.

I claim:

The ornamental design for a fishing float, as shown.
